UNITED STATES PATENT OFFICE.

EDWIN D. CHAPLIN, OF BOSTON, MASSACHUSETTS, ASSIGNOR TO INTERNATIONAL LEAD COMPANIES, A VOLUNTARY ASSOCIATION.

ELECTROLYTIC APPARATUS.

No. 906,104.

Specification of Letters Patent.

Patented Dec. 8, 1908.

Application filed February 3, 1906. Serial No. 299,240.

To all whom it may concern:

Be it known that I, EDWIN D. CHAPLIN, a citizen of the United States, and a resident of Boston, in the county of Suffolk and 5 State of Massachusetts, have invented a new and useful Improvement in Electrolytic Apparatus, of which the following is a specification.

My invention relates to apparatus where- 10 by various electrolytic processes may be carried into effect, and it relates more particularly to an apparatus for producing lead salts by electrolysis.

The object of my invention is to provide 15 a practicable apparatus whereby electrolytic processes, especially processes of producing lead salts by electrolysis, may be efficiently carried out on a large commercial scale with minimum labor.

20 With these objects in view my invention comprises an electrolytic apparatus consisting of a plurality of independent electrolytic units under central control, whereby a single operator may be placed in charge of 25 the entire plant and may regulate the operation thereof; and it comprises also an electrolyzer for each said electrolytic unit having a plurality of cells which are so constructed and arranged that a relatively high 30 potential source of electrical energy may be connected in series with said cells and the resistance of said electrolyzer cannot become sufficiently low to short-circuit said source of electrical energy.

35 Other objects of my invention will hereinafter appear and will be particularly pointed out in the appended claims.

My invention may best be understood by 40 having reference to the drawings which ac- company and form a part of this specifica- 45 tion and which illustrate one form of appa- ratus whereby the hereinbefore stated ob- jects may be realized in practice; although it will be understood that I do not wish to be limited to that particular embodiment of 50 my invention illustrated in said drawings, inasmuch as many modifications may be made therein without departing from the spirit of my invention.

55 In the drawings, Figure 1 represents a vertical longitudinal section of an electrolytic plant embodying the present invention, the section being taken on the line 1—1 of Fig. 2, looking in the direction of the ar-

row. Fig. 2 represents a vertical cross-section of said plant. Fig. 3 is a diagram hereinafter referred to for the purpose of more clearly explaining the various steps of a white lead process, which may be carried out with the apparatus shown in Fig. 3. Fig. 4 60 represents a sectional view of one of the electrolytic cells shown conventionally in Figs. 1 and 2, said section being taken on the line 4—4 of Fig. 5. Fig. 5 represents an end view of the cell shown in Fig. 4 and 65 Fig. 6 represents a side view thereof.

Inasmuch as the apparatus constituting the present invention is adapted especially for the electrolytic production of white lead, although of course it is not limited thereto, I shall first describe one process of 70 making white lead by electrolysis which may be carried out by means of said apparatus. Referring for this purpose to the dia- 75 gram shown in Fig. 3, which shows the apparatus illustrated in Figs. 1 and 2 in a conventional manner, 1 represents the supply tank containing an electrolyte which, under the influence of the electric current, will be separated into an alkaline hydrate and a 80 solvent of lead, such for example as an aqueous solution of a non-alkaline salt, preferably sodium nitrate; and containing also an oxidizing agent for preventing the formation in the electrolyte of insoluble basic 85 salts of lead, such for example as an aqueous solution of a soluble chlorate salt; or else containing an aqueous solution of a soluble salt which, under the influence of the electric current, will become an oxidizing agent, 90 such for example as an aqueous solution of a soluble chlorid salt. I shall hereinafter refer to the solution in tank 1 as the "ne- 95 tral solution" and shall assume that it consists of sodium nitrate and sodium chlorid.

3 represents an electrolyzer divided into an anode compartment 3' and a cathode compartment 3'', by means of the forami- 100 nous diaphragms 4, 4', between which is formed a compartment for receiving the electrolyte from the tank 1 through the pipe 2. For the purpose of preventing a mixture 105 of the anolyte and catholyte in the electrolyzer and consequently a precipitation of lead hydrate in the electrolyzer, I may main- tain a preponderance of pressure on the inner sides of said diaphragms, preferably, by maintaining the level of the electrolyte be-

tween the diaphragms higher than the level of the anolyte and catholyte. The level of the electrolyte in the compartment between the diaphragms, is indicated by the dotted line *e* (see Fig. 4) and the level of the anolyte and catholyte, which is governed by the height of the bends of the outlet pipes 7, 8, 7', 8', is indicated by the dotted lines *f*, *f*. In order to prevent said outlet pipes from 10 siphoning the liquids out of the electrolyzer, the upper portion of each of said bends may be provided with an opening *g*, to equalize the atmospheric pressure on the columns of liquid in the two portions of each of said 15 pipes.

The lead to be operated upon is placed in the anode compartment and may form the anode of the electrolyzer. In the present case the lead is shown in the form of a lead 20 pig 5, connected by the conductor *d* to the positive pole of the dynamo *J*, or other suitable source of current. The cathode of the electrolyzer may consist of a plate 6 of copper or other suitable metal, and is connected 25 by the conductor *c* to the negative pole of said dynamo.

As indicated in Fig. 3, I prefer to employ a number of electrolytic cells arranged at successively lower levels and having their 30 electrodes connected in series with the source of electrical energy. When the electrolyzer 3 is charged with the neutral solution and the electric current is passed therethrough, a soluble acid salt of lead is formed in the 35 anode compartment 3' and an alkaline hydrate, in the present case assumed above, sodium hydrate, is formed in the cathode compartment 3''. Presumably lead nitrate is at first formed in the anode compartment 40 and this, by the continued action of the electric current, is converted into lead oxychlorid, which is soluble at the temperature at which the electrolyte is maintained by the steam coil 30 or by other suitable means. 45 The lead oxychlorid being an acid salt of lead renders impossible the formation of insoluble basic salts of lead.

The solution in the anode compartment 3' of the cell 3, is conveyed by the pipe 8 to 50 the anode compartment 3' of the cell 3^a, and the solution in the cathode compartment 3'' of the cell 3 is conveyed by the pipe 7 to the compartment between the diaphragms 4, 4' of the cell 3^a. The solutions in the anode 55 and cathode compartments of the cell 3^a are in turn discharged by the pipes 8' 7', respectively, to the receptacles 10, 9. The solution of the acid salt of lead is conveyed from the receptacle 10 to the elevated tank 60 29 by the pump 26 and the pipe 10', while the alkaline hydrate discharged in the receptacle 9 is conveyed to the elevated tank 27 by the pump 26' and pipe 9'. The solutions in the tanks 27 and 29 are discharged

through the pipes 20 and 21, respectively, 65 into the precipitating vessel 22, which may be a glass globe, and mixed, thereby producing lead hydrate and a solution which is substantially the original neutral solution,— in the present case, sodium nitrate mixed 70 with sodium chlorate and containing probably some sodium chlorid. The pipe 31 conveys the contents of the precipitating vessel into the tank 19 below the filter 23, so that the filtrate which passes through said filter 75 may be drawn off from the upper portion of the tank 19 by the pipe 25, and discharged into the original supply tank 1. The lead hydrate is conveyed from tank 19 to the filter press 32 by the pipe 24, and the neutral solution which is squeezed out of it by the filter press, is conveyed by the pipe 33 to the tank 1. The lead hydrate may now be removed from the filter press and carbonated in any suitable manner as hereinafter more fully 80 set forth.

Referring now to Figs. 1 and 2, X represents an electrolytic plant comprising a building having five levels which carry the various tanks and receptacles above referred 90 to. The particular plant shown in Figs. 1 and 2 consists of six electrolytic units arranged in two rows of three each. Each unit is independent of every other unit, so that the plant thereby is rendered perfectly 95 extensible without changing any of its operating features. Each unit comprises a supply tank 1, an electrolyzer A, or B, or C, at a lower level than said tank, an outlet 100 from said tank to said electrolyzer, two vessels 9 and 10, at a lower level than said electrolyzer, outlet pipes 7' and 8' for discharging the alkaline hydrate and the lead solution, respectively, into the tanks 9 and 10, two pumps 26, 26' for elevating the alkaline hydrate from the tank 9 on the ground 105 floor D to the tank 27 on the top floor H, and for conveying the lead solution from the tank 10 on said ground floor to the tank 29 on said top floor, outlets 20 and 21, from said tanks 27 and 29 to a precipitating vessel 22, a filtering tank 19 for receiving the contents of said precipitating vessel, a pipe 25 for conveying the filtrate to the tank 1, a filter press 32 for receiving the precipitate 110 from the vessel 19, and a pipe 33 for conveying the liquid recovered from the precipitate in the filter press to the tank 1. Each electrolytic unit comprises also a carbon dioxid generator 12, communicating by a pipe 13 with the tank 11 for converting the alkaline hydrate discharged into said tank 11 from the tank 27 by the pipe 28 into sodium bi-carbonate; a tank 15 receiving said sodium bi-carbonate from the tank 11, through the 115 pipe 14 for converting the lead hydrate which manually or otherwise is taken from the filter press 32 into lead carbonate; a fil-

ter press 16 receiving the lead carbonate so produced through the pipe 18, and a pipe 17 for discharging into the alkaline hydrate tank 9, the sodium hydrate squeezed out of 5 the lead carbonate by the filter press 16.

In the particular plant herein illustrated there are six precipitating vessels arranged in two rows of three each, those of one row being numbered 22, and those of the other 10 row being numbered 22'. There are, as shown in Fig. 1, two rows of tanks alternately numbered 27 and 29, and each pair of tanks 27, 29, communicates with a different one of the precipitating vessels 22, 15 by means of the outlet pipes 20 and 21, respectively. Each of the pairs of tanks arranged opposite the tanks 27, 29, and one of which, 27', is shown in Fig. 2, connects, by means of correspondingly arranged pipes, 20 one of which, 20', is shown in Fig. 2, with a different one of the precipitating vessels 22'. As shown in Fig. 1, all the precipitating vessels are arranged close together, so 25 that one operator may control by means of the valves v , v' , with which said outlet pipes are provided, the operation and output of the entire plant.

The elements shown on the right hand portion of Fig. 2 are identical to those above 30 referred to, which are shown on the left hand portion of said figure, and are correspondingly numbered with primed numerals. Although I have herein shown but two rows of electrolytic units, each comprising 35 three units, it is apparent that any number of rows having a larger number of units may be employed as for example, four rows of three units each, or of five units each, and that however large the number, the 40 valves v , v' may always be so arranged as to permit all the independent units being under central control. It will be apparent also that one electrolytic unit may be shut down for cleaning the same, without interfering 45 with the operation of the plant as a whole.

In contradistinction to electrolytic plants in use at the present time, I prefer to employ 50 a dynamo electric machine J , or other source of current having a relatively high potential as compared to those heretofore employed. It has been found in practice that in carrying out processes of the kind above set forth, a multiplication of the electrolytic cells comprising 55 an electrolyzing battery results in short-circuiting the dynamo or other source of current. Heretofore in such processes, each anode compartment of such electrolyzer discharged its contents into a trough running 60 the entire length of the electrolyzer and each cathode compartment discharged its contents into a similar trough. Therefore, the electrolyzer was to a greater or less degree shunted by each of said troughs, and

when a sufficient number of cells were employed to require a generator of relatively high potential, said generator was short-circuited, the current traversing the following path,—from the positive pole to the anode compartment of the first cell, through 65 the pipe which discharges the anolyte into the aforesaid trough, through the trough to the pipe which discharges the contents of the anode compartment of the last cell into said trough, then to the cathode of said last cell and back to the generator, thereby diverting by means of the trough and the liquid flowing therein a large 70 proportion of the current delivered by said dynamo because after the cells have been 75 multiplied to a certain extent, their combined serial resistance is much greater than the resistance of the shunt afforded by said trough.

By arranging the cells which make up the 80 electrolyzers A, B, C, etc., at successively lower levels, and arranging the pipes 8 and 7 so that an anode compartment at a higher level will discharge its contents through the pipe 8 to the next anode compartment at a 85 lower level, and so that a cathode compartment at a higher level will discharge its contents through the pipe 7 into the compartment between the diaphragms 4, 4' of the next cell at a lower level, I am enabled to 90 obviate the necessity of laterally running troughs and thereby to prevent all danger of short-circuiting the generator. By so constructing and arranging the elements 3, 3^a, 3^b, etc., of each electrolyzer A, B, C, etc., 95 the resistance of said electrolyzer cannot become sufficiently low to short-circuit a source of energy having a potential relatively high as compared to those commonly employed. For example, the generator J 100 may be an ordinary electric-lighting dynamo, delivering current at 110 volts, or the terminals of the electrolyzer may be connected to an ordinary electric lighting circuit having connections to a power house. 105

When sodium-chlorid, or any other suitable soluble chlorid salt is employed in connection with the aqueous solution of a nitrate of an alkaline base to prevent the formation of insoluble lead salts in the electrolyzer, 110 lead chlorid probably is formed at one stage of the process and as this is insoluble at ordinary temperatures, it is necessary to heat the neutral solution, as more fully set forth in United States Letters Patent No. 675,555, 115 dated June 1, 1901, granted to H. G. Halloran and myself. A convenient means of maintaining the electrolyte at the desired temperature consists in the steam coil 30, shown in Fig. 3. It will be understood 120 of course that each tank 1 will be provided with such steam coil and that all coils may be connected in series with a steam genera- 125

4. Another object in heating the electrolyte is to provide a hot solution for treating the lead hydrate in the tank 15, inasmuch as a hydrated carbonate of lead is thereby produced.

5. Although for the purpose of more fully disclosing my invention I have described the same in connection with a process of making white lead in which lead hydrate is 10 first produced and is afterward carbonated, it will be understood that the electrolytic apparatus herein described is adapted to be used for carrying out direct processes of electrolytically making white lead or processes in which the lead carbonate is precipitated directly from a solution of a soluble salt of lead. Also it will be understood that my invention is not limited to processes of making lead carbonate by electrolysis, inasmuch as it is well adapted for producing 15 other salts of lead, such as lead chromate, lead oxid, etc. Furthermore in its broad aspects, my invention is not necessarily limited to processes for producing lead salts by 20 electrolysis inasmuch as many other electrolytic processes may be carried into effect thereby.

I claim:

1. In an apparatus for producing white 30 lead by electrolysis, a neutral solution tank, an electrolyzer at a lower level than said tank, an outlet from said tank to said electrolyzer, two vessels at a lower level than said electrolyzer, outlets from the anode and 35 cathode compartments, respectively, of said electrolyzer to said vessels, means for elevating the liquids discharged into said vessels from said anode and cathode compartments, each to a separate one of a pair of tanks 40 located at a higher level than the aforesaid neutral solution tank, outlets from said pair of tanks to a precipitating vessel, means in 45 said outlets for controlling the flow of liquids therethrough, said means being located so as to be within the control of a single operator, outlets from said precipitating vessel to a filtering tank located at a lower level than 50 said precipitating vessel and at a higher level than the aforesaid neutral solution tank, and an outlet for the filtrate in said filtering tank to said neutral solution tank.

2. In an apparatus for producing white lead by electrolysis, a neutral solution tank, an electrolyzer at a lower level than said 55 tank, an outlet from said tank to said electrolyzer, two vessels at a lower level than said electrolyzer, outlets from the anode and cathode compartments, respectively, of said electrolyzer to said vessels, means for elevating the liquids discharged into said vessels from said anode and cathode compartments, each to a separate one of a pair of tanks 60 located at a higher level than the aforesaid neutral solution tank, outlets from said pair of tanks to a precipitating vessel, outlets 65

from said precipitating vessel to a filtering tank located at a lower level than said precipitating vessel and at a higher level than the aforesaid neutral solution tank, and an outlet for the filtrate in said filtering tank to said neutral solution tank.

3. In an apparatus for producing lead salts by electrolysis, a plurality of electrolyzing units, a plurality of pairs of tanks, means for conveying the contents of the 75 anode and cathode compartments, respectively, of each electrolyzing unit to each member of a different one of said pairs of tanks, a plurality of precipitating vessels, each associated and operatively connected 80 with a different one of said pairs of tanks, and means located so as to be under the control of a single operator for regulating the flow of liquids from each of said pairs of tanks into a different one of said precipitating 85 vessels.

4. In an electrolytic apparatus, a relatively high potential electrical generator, an electrolyzer comprising a plurality of cells arranged at successively lower levels, means 90 dividing each cell into an anode compartment, a cathode compartment and an intermediate compartment, pipe connections from the anode compartment of each cell to the anode compartment of the cell at the next 95 lower level, and other pipe connections from the cathode compartment of each cell to the intermediate compartment of each cell at the next lower level, and means connecting said cells in series with said generator.

5. In an apparatus for producing white lead by electrolysis, a neutral solution tank, an electrolyzer at a lower level than said tank, an outlet from said tank to said electrolyzer, two vessels at a lower level than said electrolyzer, outlets from the anode and cathode compartments, respectively, of said electrolyzer to said vessels, means for elevating the liquids discharged into said vessels from said anode and cathode compartments, each to a separate one of a pair of tanks located at a higher level than the aforesaid neutral solution tank, outlets from said pair of tanks to a precipitating vessel, means in 110 said outlets for controlling the flow of liquids therethrough, said means being located so as to be within the control of a single operator, and outlets from said precipitating vessel to a filtering tank located at a lower 115 level than said precipitating vessel.

6. In an apparatus for producing white lead by electrolysis, a neutral solution tank, an electrolyzer at a lower level than said tank, an outlet from said tank to said electrolyzer, two vessels at a lower level than 120 said electrolyzer, outlets from the anode and cathode compartments, respectively, of said electrolyzer to said vessels, means for elevating the liquids discharged into said vessels from said anode and cathode compartments,

each to a separate one of a pair of tanks located at a higher level than the aforesaid neutral solution tank, outlets from said pair of tanks to a precipitating vessel, means in 5 said outlets for controlling the flow of liquids therethrough, said means being located so as to be within the control of a single operator, outlets from said precipitating vessel to a filtering tank located at a 10 lower level than said precipitating vessel, and means for conveying the filtrate from said filtering tank to said neutral solution tank.

7. In an apparatus for producing white 15 lead by electrolysis, a neutral solution tank, an electrolyzer at a lower level than said tank, an outlet from said tank to said electrolyzer, two vessels at a lower level than said electrolyzer, outlets from the anode and cathode compartments, respectively, of said electrolyzer to said vessels, means for elevating the liquids discharged into said vessels from 20 said anode and cathode compartments, each to a separate one of a pair of tanks located at a higher level than the aforesaid neutral solution tank, outlets from said pair of tanks to a precipitating vessel, and outlets from 25 said precipitating vessel to a filtering tank located at a lower level than said precipitating vessel.

8. In an apparatus for producing white lead by electrolysis, a neutral solution tank, an electrolyzer at a lower level than said

tank, an outlet from said tank to said electrolyzer, two vessels at a lower level than 35 said electrolyzer, outlets from the anode and cathode compartments, respectively, of said electrolyzer to said vessels, means for elevating the liquids discharged into said vessels from the anode and cathode compartments, 40 each to a separate one of a pair of tanks located at a higher level than the aforesaid neutral solution tank, outlets from said pair of tanks to a precipitating vessel, outlets from 45 said precipitating vessel to a filtering tank located at a lower level than said precipitating vessel and means for conveying the filtrate from said filtering tank to said neutral solution tank.

9. In an apparatus for producing lead 50 salts by electrolysis, an electrolyzing unit, a pair of tanks, means for conveying the contents of the anode and cathode compartments, respectively, of said electrolyzing unit each to a different one of said tanks, a precipitating vessel associated and operatively connected with said pair of tanks, and means for regulating the flow of liquids from 55 said pair of tanks into said precipitating vessel.

In testimony whereof, I have hereunto 60 subscribed my name this 20th day of January 1906.

EDWIN D. CHAPLIN.
